TUBULAR ELASTIC FABRIC AND PROCESS
OF MAKING SAME

Robert E. Davis, Fort Payne, Ala., assignor to
W. B. Davis & Son, Incorporated, Fort Payne,
Ala., a corporation of Alabama

Application September 15, 1938, Serial No. 230,121

7 Claims. (Cl. 66—9)

This invention relates to knitted fabrics having elastic yarn incorporated in predetermined courses of the stitches of which the fabric is composed. The invention particularly relates to 5 ribbed fabrics with rubber, bare or covered, laid in successive or relatively spaced stitch courses between the stitch wales on one face of the fabric and the stitch wales on the opposite face thereof. The invention in its broader aspects however is applicable to the knitting of non-ribbed 10 fabrics.

Knitted fabrics having rubber incorporated in the stitch courses contracts excessively in a coursewise direction, due to the fact that in drawing 15 the rubber from its supply, such as a spool etc., the rubber is unavoidably placed under tension and is stretched thereby prior to, as, and when it is being incorporated in the fabric.

When knitted fabric is released from the knitting needles it inherently contracts to some extent when there is no rubber incorporated therein, but, when the fabric contains rubber yarn, the tension on the rubber is released with the knitting tension of the fabric and immediately contracts with and to a greater extent than the normal contraction of the fabric. This causes the fabric to be abnormally contracted.

Complicated and expensive laying-in and other rubber feeding attachments have been devised 30 for feeding rubber into knitted fabrics under zero tension which have functioned with various degrees of success but which at the best have required constant attention to maintain in adjustment.

Manufacturers of hosiery and other tubular knitted structures in order to obtain a normally sized finished product, such as a stocking top for example, which would ordinarily be made on a three and one-half inch diameter machine and 35 which if the fabric contained no rubber would normally contract to say about a two and one-half inch diameter, but which when rubber is incorporated therein contracts to about a one and one-half inch diameter, have resorted to 40 knitting the fabric on a machine of about a five inch diameter. Such a machine will produce a finished rubber-containing fabric of a normal two and one-half inch diameter. These figures are here given for the purpose of comparative illustration only and are not intended to represent any accurately calibrated actual examples.

The object of the present invention is to provide a simple process and inexpensive apparatus for laying rubber in knitted fabric or for 45 feeding it to incorporating mechanism under

positive zero or light tension, or, if desired, under longitudinal compression whereby, with the former, the fabric, after knitting, may contract only to its normally inherent extent, or, with the latter, the fabric may retain approximately 5 the same size it obtained during knitting or be expanded coursewise, i. e. the coursewise dimension corresponding to the overall length of the needle bed or circumference of the cylinder and/or dial may be retained in the fabric with 10 the stitch wales spaced apart laterally to the same extent as the needles, or the coursewise dimension of the fabric and the lateral spacing of the wales may be decreased, or increased, depending upon the adjustment of the simple mechanism forming the basis of the present invention. 15

In the accompanying drawings:

Fig. 1 diagrammatically illustrates a swatch of 20 ribbed fabric with rubber laid in successive courses thereof in accordance with the principles of the present invention;

Fig. 2 diagrammatically illustrates, in plan, 25 the cylinder and dial of a circular rib knitting machine equipped to produce the fabric of Fig. 1;

Fig. 3 diagrammatically illustrates a linear development of a portion of the cylinder and dial with the needles thereof being manipulated in accordance with the principles of the present invention to produce the fabric of Fig. 1; and 30

Fig. 4 diagrammatically illustrates the cam ring and path of the butts of the cylinder needles for actuating the cylinder needles in the manner indicated in Fig. 3.

As shown in Fig. 1 the fabric F consists of successively interknit courses c1, c2, c3, c4, c5, etc. of stitches s and s' respectively forming wales w and w' on opposite faces respectively of the fabric. 35

In the present illustration, Fig. 1, there is a 40 rubber strand R inlaid in each of the stitch courses. It will be understood that this is the result of using a single feed circular machine such as disclosed in Figs. 2, 3 and 4 of the drawing. However, if a multiple feed machine is used there may be a rubber inlaying finger, tube, eye, etc., at each or at any desired number of such feeds, in which case the rubber R would be laid in each course or in as many relatively spaced courses as there would be rubber feeds adjacent thread feeds. For example, in a two feed machine with a rubber feed at only one thread feed the rubber R would be laid in only every alternate course, or in every third course in a three 45 50 55

feed machine provided with a rubber feed at only one thread feed, and so on.

As shown in Figs. 2 and 3, a needle cylinder 10 with needles 11 in the grooves 12 thereof operates with a dial 20 having needles 21 operating in the grooves 22 thereof.

The cylinder needles 11 occupy the normal rest or tuck position with the butts 13 thereof resting on a rest cam 14 in the cam ring, as shown in Fig. 4. These needles would be ordinarily raised to clearing position by a clearing cam 16. At the high position, the needles would take the knitting yarn Y in their hooks 17 whereupon the needles 11 would be lowered to casting position by the usual stitch cam 18, to form the stitches s of the wales w.

The dial needles would be actuated in the usual manner to take the knitting yarn Y in their hooks 23 from between adjacent cylinder needles 11 as the latter descended in their respective grooves 12 and would be projected previously thereto and retracted concurrently with the descent of the cylinder needles by the usual cams carried by the dial cap 24, shown in plan in Fig. 2. These cams being usual and no variation in the normal travel of the dial needles being required in carrying out the present invention, the dial needles cams in the cap 24 have been eliminated from the drawings.

30 In carrying out the present invention the rubber yarn R is fed to the machine at some distance ahead of the feeding of the knitting yarn Y to the needles, as shown in Fig. 2, while the cylinder needles are at rest with their hooks 35 above the top edge 19 of the cylinder 10.

The rubber R may be drawn from any suitable source such as a spool, bobbin or other package or from a loose pile lying on a suitable support or confined in a suitable container. No heed need be paid to the degree of tension on the strand R or the lack of tension, beyond assuring that the rubber is running freely and with a fair amount of uniformity to the needles.

40 The rubber strand R is fed to the cylinder needles 11 against the outer faces 9 thereof below the hooks 17 and above the upper edge 19 of the cylinder 10. Due to the curvature of the cylinder the rubber R bears against the outer faces 9 of the needles 11, and is laid on the top edge 19 of the cylinder, in a segment or sector R', radially beyond and concentric to the circle of the fabric F where it forms against or between the inner surface of the cylinder 10 and the outer peripheral edge of the dial 20, thus the arc of the rubber strand segment R' is of greater radius than the fabric circle, thus, a complete circle of rubber is of greater diameter than the diameter of the knitting circle of the fabric and if laid in the fabric with zero tension the rubber will tend to retain the fabric at its knitting diameter or tend to increase beyond its knitting diameter.

45 Normally in laying rubber in ribbed fabrics it is laid behind the cylinder needles and against the peripheral edge of the dial, which at the outset makes the diameter of a circle of the rubber, at zero tension, less than the knitting diameter of the fabric.

In order to insure zero tension on the rubber R or in order to place the rubber under longitudinal compression within the fabric, according to the present invention, the rubber is drawn down in successive loops or festoons L into the tops of the cylinder needle grooves 12 by the needle hooks 17 of the needles 11, around the tops 8 of the ribs or partitions 7 which are formed

between adjacent needle grooves 12, as clearly shown at R2 in Figs. 2 and 3.

Where the rubber is first engaged by the hook of a needle and pulled down into a groove 12 the rubber is placed thereby under tension and this tension reacts to draw rubber from the supply. The depth to which the rubber is drawn into the top of the groove, i. e. the length of each loop L, controls the degree of tension placed on the rubber and this in turn controls the amount of rubber drawn from the supply.

In order to keep the initial tension from reacting in the opposite direction to withdraw the rubber from the fabric a plurality of the loops L of the rubber are held down in a number of adjacent needle grooves, which snubs the rubber and prevents it from moving one way or another within the sector R2, which may be termed the holding sector.

20 The needles 11 are lowered to the desired extent in the grooves 12 to draw the desired amount of rubber from the supply, by a draw cam 25, the introduction of which into the cam ring constitutes practically the only change that is required to be made in a normal machine in order 25 to work the method of the present invention.

If desired, a lift cam 26 may be introduced ahead of the draw cam 25 to lift the needles slightly to insure the rubber passing below the hooks 17 of the needles. This, however, in some 30 instances at least, may be eliminated.

At the distant end of the holding sector R2 the needles 11 are raised by the ordinary clearing cam 16. The raising of the needles slacks the tension on the rubber R before it is laid in 35 the fabric, consequently, in the sector R2, the rubber lays on the top edge 19 of the cylinder 10 in a completely relaxed state, or under any degree of tension desired depending to what extent the lower edge 25a of the draw cam has been 40 previously lowered with respect to the top edge 14a of the rest cam 14.

The rubber R in the sector R3, relaxed as a result of the needles 11 being raised by the clearing cam 16 to take the knitting yarn Y, retains 45 its relaxed condition and lays idly on the top 19 of the cylinder 10 in front of the raised cylinder needles 11 and under the dial needles 21, which at this stage are projected by their own projecting or clearing cams.

50 As the cylinder needles 11 are again lowered by the stitch cam 18 to pull the newly received knitting yarn Y through the stitches s then hanging on the shanks of these needles, and the dial needles 21 are coordinately retracted to take the 55 knitting yarn Y and form it into loops or stitches s1 by drawing it through the stitches then hanging therein, the relaxed rubber R, due to the curvature of the cylinder and dial and to the casting of the stitches and rubber over the points 60 of the needles as the needles are lowered by the stitch cam 18, slides inwardly over and from the top 19 of the cylinder 10 in an inlaying sector R4, onto those portions s2 of the knitting yarn Y which connect the stitches s of the cylinder 65 wales w with the stitches s1 of the dial wales w1 and lays in this position idly and relaxed clear around the cylinder to the feed for the yarn Y, whether it be the next feed on a multi-feed machine or the same feed of a single feed 70 machine as shown in Figs. 2 and 3.

In the meantime the cylinder needles have again been raised to the rest position by the incline 14b of the rest cam 14, this time outside the rubber R which moves the rubber R into the 75

in-laid position, in sector R4, in the fabric between the wales w and w1. The dial needles at the same time move out to a corresponding rest position between the cylinder needles, above, 5 the yarn R, and hold it against vertical displacement while the raised cylinder needles hold it against radial displacement.

The relaxed rubber ring lays on top of the stitch connectors s2 until the needles at the next 10 feed of knitting yarn Y are operated and the needles, after clearing, take the yarn and form it into the stitches of the next course, whereupon the connectors s2 of the new course are formed over the rubber R then lying in a relaxed state on the connectors s2 of the previous course, as clearly 15 shown at Z in Fig. 3.

From the above it will be clear that by drawing the rubber down into the needle grooves to a greater or lesser extent before it is laid in the 20 fabric a sufficient amount of the rubber R is drawn from the supply each time by each needle to equalize or exceed the amount of elongation 25 of the rubber created by the tension on the rubber resulting from drawing the rubber from its supply spool, etc., thus, if equalizing amounts are drawn by the needles the rubber circle or spiral convolution thereof as laid in each course of 30 stitches will coincide in diameter with the knitting diameter or circumference of the knitting circle of the fabric, thus the knitting circle of the fabric will be retained.

If slightly less than equalizing amount of rubber are drawn by the needles the diameter of the rubber ring will decrease somewhat below 35 the knitting diameter of the fabric and the fabric circle will contract normally as it would inherently in cases where no rubber is inlaid in the fabric.

If excessive amounts of rubber R are drawn 40 by the needles each time the diameter of each rubber ring or spiral convolution will exceed the knitting diameter of the fabric and the fabric will under such conditions expand coursewise to a size greater than that of the knitting diameter.

This condition, i. e. the coursewise expansion 45 of the fabric, obviously is made possible by a walewise contraction when the pull of the drawing-off rolls or the drawing-off weight, which 50 normally places the fabric under walewise tension to effect casting of the stitches from the needles, is released.

The above description of the present invention has been confined to the knitting of ribbed fabrics however insofar at least as concerns the 55 drawing of the rubber from its supply by feeding it under the hooks of a set of knitting needles, lowering the needles to draw the rubber into loops or festoons in the needle grooves over the tops 60 of the partitions between the grooves or the equivalent thereof, and then raising the needles successively to release the rubber in a relaxed state 65 prior to incorporating the rubber in the fabric, the invention is equally applicable to machines for knitting plain, i. e. non-ribbed fabric on a single bank of needles, the subsequent incorporation of the rubber into the fabric as by actual 70 knitting of the rubber itself into stitches or otherwise, in ways known to the art being merely coincidental to the preparation of the rubber for such incorporation as disclosed above.

I claim:

1. The method of placing rubber yarn in knitted 75 fabrics, which consists in feeding the rubber under the hooks of the needles knitting the

fabric while the needles are in tucking position, successively lowering the needles to pull the rubber into the needle grooves over the tops of the partitions between said grooves to measure and form the rubber into loops therein and thereby 5 draw the rubber from a supply thereof, and raising the needles successively at least to said tucking position to release the rubber prior to incorporating the rubber in the fabric.

2. The method of placing rubber yarn in knitted 10 fabrics, which consists in feeding the rubber under the hooks of the needles knitting the fabric while the needles are in tucking position, successively lowering the needles to pull the rubber into the needle grooves over the tops of the partitions between said grooves to measure and form the rubber into loops therein and thereby draw 15 the rubber from a supply thereof, holding the rubber in said loops in a plurality of said grooves, and raising the needles successively at least to 20 said tucking position to release the rubber prior to incorporating the rubber in the fabric.

3. The method of placing rubber yarn in knitted 25 fabrics, which consists in feeding the rubber under the hooks of the needles knitting the fabric while the needles are in tucking position, successively lowering the needles to pull the rubber into the needle grooves over the tops of the partitions between said grooves to measure and form the rubber into loops therein and thereby draw 30 the rubber from a supply thereof, holding the rubber in said loops in a plurality of said grooves, raising the needles successively at least to said 35 tucking position to release the rubber prior to incorporating the rubber in the fabric, raising the needles to clearing position, feeding knitting yarn to the raised needles with the relaxed rubber in front of the needles and below the latches thereof, and lowering the needles to draw the knitting 40 thread through loops previously formed and hanging on the needles and to cast said loops and said rubber over the points of the needles to the backs thereof.

4. The method of placing rubber yarn in knitted 45 fabrics, which consists in feeding the rubber under the hooks of the needles knitting the fabric while the needles are in tucking position, successively lowering the needles to pull the rubber into the needle grooves over the tops of the partitions between said grooves to measure and form the rubber into loops therein and thereby draw 50 the rubber from a supply thereof, holding the rubber in said loops in a plurality of said grooves, raising the needles successively at least to said 55 tucking position to release the rubber prior to incorporating the rubber in the fabric, raising the needle to clearing position, feeding knitting yarn to the raised needles with the relaxed rubber in front of the needles and below the latches thereof, lowering the needles to draw the knitting 60 thread through loops previously formed and hanging on the needle and to cast said loops and said rubber over the points of the needles to the backs thereof and knitting stitches of a succeeding course into those cast over the points 65 of said needles with said rubber to effect incorporation of the rubber in the fabric.

5. The method of placing rubber yarn in knitted 70 fabrics, which consists in feeding the rubber under the hooks of the needles knitting the fabric while the needles are in tucking position, successively lowering the needles to pull the rubber into the needle grooves over the tops of the partitions between said grooves to measure and form the rubber into loops therein and thereby draw 75

the rubber from a supply thereof, holding the rubber in said loops in a plurality of said grooves, raising the needles successively at least to said tucking position to release the rubber prior to incorporating the rubber in the fabric, raising the needle to clearing position, feeding knitting yarn to the raised needles with the relaxed rubber in front of the needles and below the latches thereof, lowering the needles to draw the knitting thread through loops previously formed and hanging on the needle and to cast said loops and said rubber over the points of the needles to the backs thereof, knitting stitches of a succeeding course by said needles into the stitches cast over the points of said needles with said rubber to effect incorporation of the rubber in the fabric.

6. The method of placing rubber yarn in knitted fabrics, which consists in feeding the rubber under the hooks of the needles knitting the fabric while the needles are in tucking position, successively lowering the needles to pull the rubber into the needle grooves over the tops of the partitions between said grooves to measure and form the rubber into loops therein and thereby draw the rubber from a supply thereof, holding the rubber in said loops in a plurality of said grooves, raising the needles successively at least to said tucking position to release the rubber prior to incorporating the rubber in the fabric, raising the needle to clearing position, feeding knitting yarn to the raised needles with the relaxed rubber in front of the needles and below the latches

thereof, lowering the needles to draw the knitting thread through loops previously formed and hanging on the needle and to cast said loops and said rubber over the points of the needles to the backs thereof, knitting stitches of a succeeding course by said needles into the stitches cast over the points of said needles with said rubber to effect incorporation of the rubber in the fabric and operating the needles to draw and hold the rubber prior to the knitting of the stitches of each course on and by said needles.

7. The method of placing rubber yarn in knitted fabrics, which consists in successively forming the rubber into a series of immediately adjacent elongated loops between relatively fixed supports for the loops to measure and place the rubber under tension and draw said rubber from a suitable supply prior to the feeding of the rubber to the knitting point of the fabric, varying the extent of elongation of said loops to control the length of the rubber relative to the length of each course of stitches of the knitted fabric in which the rubber is incorporated for establishing a predetermined tensional relationship between the rubber and the fabric coursewise thereof and releasing said loops successively from one end of said series to relieve the rubber of said tension for delivering it in a substantially relaxed state to said knitting point.

ROBERT E. DAVIS.
